UNITED STATES PATENT OFFICE.

FRANK B. YINGLING, OF HAMILTON, OHIO.

TUBE-MACHINE.

1,258,731.

Specification of Letters Patent. Patented Mar. 12, 1918.

Application filed March 1, 1917. Serial No. 151,652.

To all whom it may concern:

Be it known that I, FRANK B. YINGLING, a citizen of the United States, and a resident of the city of Hamilton, in the county of Butler and State of Ohio, have invented certain new and useful Improvements in Tube-Machines, of which the following is a specification.

This invention relates broadly to tube machines and more particularly to a machine of this character adapted to make tubes used in the manufacture of paper kegs, containers and the like.

The principal object of this invention is to provide a machine for producing tubes composed of superimposed layers of firmly united strips of paper or like material wrapped in spiral relation one upon the other.

20 A further object of this invention is to provide a machine for producing tubes of the character above described of varying diameters, from strips of paper of uniform width.

25 A further object of my invention is to provide an applicator, for applying an adhesive material to a strip of paper, and connecting the same with a guide roll so that the two may be moved in unison to change the direction of travel of the strip of paper with relation to the mandrel.

Another object of the invention is to provide winding belts mounted on frames which may be simultaneously or independently adjusted manually in accordance with the size of tube to be produced.

35 Still another object of my invention is to provide an applicator frame made in two sections and having the upper section movable relatively to the lower section without interfering with the travel of the paper therethrough.

40 A still further object of this invention is to provide a brake roll so disposed in the applicator frame that a uniform tension may be maintained on the paper passing therethrough.

These objects together with attendant advantages will in part be obvious and will in 45 part be pointed out in the specification hereinafter following and the drawings forming a part thereof throughout the several views of which like characters of reference have been used to indicate like parts.

55 Figure 1 is a top plan view of my improved machine.

Fig. 2 is an end elevation thereof, part of the apparatus being shown diagrammatically.

Fig. 3 is a side view of one type of applicator employed. 60

Fig. 4 is a side view of another type of applicator.

Fig. 5 is a top view of one of the winding frames. 65

Fig. 6 is a side view of the construction shown in Fig. 5.

Fig. 7 is an enlarged detail view showing the driving connection for one of the belt pulleys of the winding frame. 70

Fig. 8 is an enlarged detail view of an adjusting wheel.

Fig. 9 is an enlarged view of the applicator for applying paraffin.

Fig. 10 is a detail view of the driving mechanism for the paraffin bar. 75

Fig. 11 is a detail view of the oscillating mechanism for the paraffin bar.

In machines for producing tubes in continuous lengths from strips of paper wound on a mandrel in superposed relation it is necessary that the strips be wound spirally, the pitch of the spiral being dependent upon the diameter of tube to be produced, and the width of the paper. In order that 80 my machine may be utilized for the purpose of producing tubes of varying diameters depending merely upon the capacity of the machine and the diameter of the mandrel employed, I have provided means for 85 changing at will the mandrel, and the angle at which each individual strip approaches the mandrel to thereby vary the pitch of the spiral and render it possible to make tubes having diameters varying between 90 95 comparatively wide limits, with the same width paper.

In order to cause the different layers of paper composing the tube to become firmly united, and the strips assume their proper 100 positions on the mandrel, winding means are employed, comprising belts adapted to pass around the mandrel and the tube being formed thereon. To insure the successful making of tubes it is essential that these winding belts should also assume a spiral relation to the mandrel, which relation must be changed for each different diameter of tube being made. This change may be accomplished in my machine by means of adjusting rods and hand-wheels connected thereto which permit simultaneous or inde- 105 110

pendent adjustment of each of the winding frames.

Referring more particularly to the drawings, the main frame of my tube machine 5 comprises a supporting base 1 mounted on a floor or platform 2. Adjacent one end of the machine there is provided a pair of standards 5 the upper ends 6 of which form bearings for the mandrel 7 upon which the 10 tubes are formed. These bearings are preferably formed in two parts to make removal and substitution of mandrels comparatively easy. When a smaller mandrel is employed, packing bushings are inserted, while if a 15 larger mandrel is used, part of the bushings are removed.

The paper strips for forming the tubes are fed from large rolls 8 rotatably mounted in racks 9 positioned at each side of the 20 machine. From all of these rolls, with the exception of the one supplying paper to applicator B', the paper passes through applicator frames where it receives a coating of adhesive material, and thence over 25 suitable guide rolls to the mandrel. Applicator B', to be hereinafter described, supplies a coating of paraffin to the paper passing therethrough to prevent the same from sticking to the mandrel. The applicators employed on opposite sides of the 30 mandrel, while resembling each other in the general outline and function performed, differ in their specific embodiments. For the sake of convenience I have designated 35 the applicators shown on the right of the mandrel in the plan view by the reference character A, and the mandrels shown on the left by the reference character B. Since all of the applicators A, of which any number 40 may be employed depending only upon the thickness of the tube it is desired to produce, are alike in construction it will only be necessary to refer specifically to one which is shown particularly in Fig. 4 of the 45 drawings. This applicator comprises an upper frame 10 pivotally secured to a lower frame member 11 by the pivot 12 carried by the bracket members 14 projecting from the sides of the upper and lower frame members 50 respectively. Locking devices 15 are provided for holding the frame in adjusted position. The purpose of the pivotal connection and the reason for its precise location will be apparent upon further describing 55 the operation of the machine. The paper P passes transversely through each of the applicator frames, beneath the lower rolls 16 to the upper rolls 17 and thence around the brake rolls 18 to the guide rolls 60 hereinafter described. Each brake roll 18 is preferably provided with a flange 19 on one side thereof around which is positioned a brake band 20, the ends of which are yieldingly forced together by a spring device 21, the tension of which may be varied at will 65

by means of the thumb nut 22. The brake band may be secured as at 23 to the applicator frame to prevent the same from rotating with the brake roll. By means of this construction it is possible to maintain an even tension on the paper strip as the same is fed to the mandrel. During its passage around the brake rolls, the paper is brought into contact with a transfer or distributing roll 24 which receives a supply of adhesive 75 material from a pick-up roll 25 driven by a pulley 26, and journaled in such manner that a portion of its periphery is immersed in the adhesive solution supplied to the pan 27 in the manner hereinafter to be described. 80

Each of the applicators B also preferably comprises an upper frame member 28 pivotally connected to a lower frame member 29 by the pivot 30 located, in this instance, within the sides of the frame. The upper 85 frame member may be held in its adjusted position with relation to the lower frame by means of set screws or equivalent locking devices 31. The paper supplied from the large roll passes around a lower 90 roll 32 to an upper roll 34 and thence around the brake roll 35 which is provided with a tension mechanism 36 similar to those described in connection with the applicators A. The paper from the brake roll passes 95 beneath a top or press roll 37 to the guide rolls located adjacent the mandrel. During its passage beneath the press roll the paper is brought into contact with a transfer or distributing roll 38 receiving a supply of adhesive material from the pick-up 100 roll 39 driven by the belt pulley 40. With the exception of applicator B', the pick-up roll receives its supply of adhesive from the pan 41.

Applicator B' may supply the paper with a paraffin coating from a bar of paraffin carried thereby, and traveling from side to side of the applicator frame. The mechanism for accomplishing this is shown particularly in Figs. 9 to 11. As herein shown applicator B' preferably comprises an upper frame member 28' pivotally mounted on the lower frame member 29' in a manner similar to the mounting of applicators B already described. Transversely mounted between the side frames of the paraffin applicator is a supporting bar 30' to which is pivotally secured the arm 31'. The arm at its outer end preferably carries a bracket 32' in which the holder 33' for the paraffin 34' is slidably mounted on the rods 35', the paraffin being normally forced into yielding engagement with the paper strip by the springs 36'. The bar of paraffin may be readily removed or adjusted as found necessary, by loosening the thumb nut 37'.

The arm 31' may be oscillated so as to move the bar of paraffin transversely of the strip of paper as it passes through the ma- 130

chine, by providing a pitman 38' pivotally attached to the bar, and secured at its outer end to the crank wheel 39'. For different widths of paper, it is desirable to have the 5 amplitude of movement of the paraffin bar increased or decreased in proportion. As shown in the drawing this may be accomplished by securing the pitman to any one of the openings 40', each of which is disposed at a different distance from the axis of rotation of the crank wheel.

Any suitable means for rotating the crank wheel may be provided such as a vertical shaft 41' driven from the longitudinally extending shaft 100, through bevel gears 42'. A clutch connection 43', may be employed to advantage, one of the members of which is movable into and out of operative engagement by the bell crank lever 44' working in 20 the groove 45' and operable by throwing the pivoted handle 46' upwardly or downwardly. From the foregoing it will be apparent that a coating of paraffin may be applied to the surface of the strip of paper 25 adapted to contact with the mandrel and thus eliminate any tendency to stick.

The transfer or distributing rolls of all of the applicators are each mounted in a frame 42 pivoted concentrically with the axis of rotation of the pick-up rolls so that during oscillatory movement of the frame, peripheral contact between the rolls may be maintained. The upper ends of the frame are provided with adjustable stops 44 adapted to control 35 the distance between the transfer rolls and the brake rolls of applicators A, and the transfer rolls and the press rolls of applicators B respectively. When it is desired to renew the paper in the applicators, the 40 frames 42 are swung against the rear stops 45 shown in Fig. 4 so as to move the transfer rolls out of operative position with relation to the paper passing through the machine.

The paper after having received the paraffin or adhesive coating, passes from the applicators to guide rolls 46 positioned adjacent the mandrel. The paper from the applicators A passes over the guide rolls, while the paper from applicators B passes under 50 the guide rolls, this difference being necessitated by reason of the coating covering one side of each of the paper strips, with the exception of a narrow central strip S on the paper passing through applicator A'. This strip is adapted to overlie the joint formed in the paraffined layer lying next to the mandrel. This strip is left uncoated by providing a peripheral groove in the face of the transfer rollers or by making the rollers 55 in two separate pieces suitably spaced one from the other. The guide rolls are rotatably journaled in brackets 47 having a pivotal connection 48 with supports 49 slidably mounted on the base member 1.

65 For connecting the upper frame portions

of the applicators to their respective guide rolls so that the two may be moved as a unit, there may be provided side bars 50 rigidly attached at one end to the applicator frame and reinforced throughout the length by 70 cross arms 51. At their opposite ends the side bars have a pin and slot connection 52 with the brackets in which the guide rolls are journaled. These pin and slot connections accommodate for the change in distance between the pivots of the applicator frames and the pivots of the guide roll brackets, which change is caused by sliding the supports 49 along the base member. This adjustment may be accomplished by providing longitudinally extending rods 53 secured in any desired manner to the supports 49 through which they pass, and slidably mounted in a cross arm 54 at one end. The rods are preferably threaded at this end and provided with hand wheels 55 which may be turned for advancing or retracting the rods to simultaneously adjust all of the guide rolls. In order to permit individual adjustment of the guide rolls to accommodate for 80 varying thicknesses of the paper there may be provided handwheel turnbuckles 56 between each adjacent set of guide rolls. This sliding movement of the supports 49 is accomplished by a turning movement of the 85 guide roll brackets on the pivots 48, and of the upper portions of the applicator frames on the pivots 12 and 30 respectively.

It will be apparent that this turning movement of the upper portion of the applicator frames relative to the lower supporting portions must not be accompanied by any distortion of the paper passing therethrough over the upper and lower rolls. It is for this reason that the pivots of the applicator frames are positioned as close as possible to the line of travel of the paper. It has been found that within the limits of movement allowed, that the upper and lower rolls are not materially displaced out of 100 alignment, and that the paper passes thereover freely in any position to which the frames may be adjusted. By placing the pivot outside or around the paper, the pivot center can be brought into exact line with 105 the paper.

For supplying adhesive in liquid form to the pans in which the pick-up rolls of the applicators rotate, there is provided a reservoir 57 adapted to contain silicate of soda or 110 the like, and having a pipe line connection 58 with the respective pans of the applicators, with the exception of applicator B', which pans are in turn connected by cross pipes 59. The silicate of soda is forced from the reservoir and maintained in circulation by means of a pump 60. The liquid in each of the pans may be maintained at a constant level by providing stand pipes 61 forming 115 overflow outlets therefor.

For winding the strips of paper on the mandrel and properly compressing the same to form a compact tube, there may be provided a series of winding frames comprising transverse bases 62 supported on bearing plates 64 carried by the main frame 1 of the machine. The winding frames are rotatably mounted on the bearing plates around bushings 65 extending therethrough. 5

10 Adjacent the opposite ends of the frame there are provided carriages 66 adapted to support the belt pulleys 67. Each of these carriages is adjustable toward and from the axis of rotation of the base by means of 15 feed screws 68 passing through interiorly threaded blocks 69 secured to the carriages. Any form of operating means such as hand wheels 70 may be provided for operating the feed screws. The pulleys 67 are adapted 20 to support and drive the winding belts 71, and the purpose of making the carriages adjustable is to provide a tension regulating means for the belts. For rotating the guide frames around the bushings 65 so as to 25 change the spiral relationship existing between the belt and the mandrel around which they pass, there may be provided longitudinally extending rods 72 passing through the carriages 66 and journaled at 30 their forward ends in the cross arm 54. The rods 72 may be secured to the parts 66 by providing collars on each side of the arms 66, or by forming a pivotal connection for the rods in each of said arms 66. Each 35 of these rods is provided with an adjusting wheel 74 corresponding in function and operation to those described in connection with the adjusting rods 53. Individual adjustment of the winding frames is accomplished by turn buckles 75 such as clearly 40 illustrated in Fig. 8 of the drawings.

The driving mechanism for my improved machine comprises a longitudinally extending shaft 76 operatively driven from the 45 motor 77 by means of a driving belt or sprocket 78. The rotation of the shaft may be governed through the medium of a clutch 79 and its controlling member 80. Secured on the shaft 76 adjacent each of the winding frames is a bevel gear 81 adapted to mesh with the gear 82 secured to the vertical jack shaft 84. Each of these jack shafts is rotatably mounted in the bushing 65 and carries on its upper end a driving pinion 85 for the gears 86 on the cross shafts 87. The cross shafts are preferably supported in bracket bearings 88 adjacent their central portions, and have their opposite ends passing through the bevel gears 89 which are provided with extensions journaled in the belt carriages. A slideable driving connection in the form of a key and slot 90 may be provided between the cross shafts and the bevel gears. Each of the gears 89 60 is in mesh with the gears 91 on the pulley 65

shafts 92. By reason of the particular form of driving connection it will be apparent that the turning of the frame in no manner interferes with the continued operation of the machine.

The belt pulleys of the applicator frames, which have already been described, are also adapted to be driven by the motor 77. This is accomplished by providing a belt 94 operatively driven from the shaft 76 and in turn 75 transmitting power to the gear train 95, the last gear of which is in driving relation with the bevel gear 96. This gear drives the shaft 97 through the medium of gear 98 splined thereto, and which is in turn 80 operatively connected to longitudinally extending shafts 100 positioned beneath the applicator frames and receiving power through the bevel gears 99. At suitable intervals on the shafts 100 are driving pulleys 85 101 adapted to align with and constitute driving means for the belt pulleys 26 and 40 of the applicator frames A and B respectively.

From the foregoing description taken in 90 connection with the drawings it is believed that the operation of the machine is obvious. This operation may be briefly summarized by stating that each strip of paper except that through applicator B', passes from the 95 supply roll through an applicator frame where it receives an adhesive coating on one side thereof and is then led to a mandrel around which it is wound and pressed into proper position by means of winding belts. 100 When it is desired to change the diameter of the tubes made by the machine, and still employ paper of the same width, it is only necessary to insert a new mandrel in the bearings 6, and to adjust the angle of approach of the paper to such mandrel so that the pitch of the spiral in which it is wound thereon will be suitably decreased or increased. At the same time the winding belts are adjusted so as to act on the paper 110 at the most effective angle.

Although I have illustrated and described the preferred form of my invention it will be obvious that many changes may be made therein without departing from the spirit 115 of the invention and the scope of the appended claims.

What I claim is:—

1. In a tube machine, a mandrel, means for simultaneously feeding strips of paper 120 to said mandrel from the same side, and means for changing at will the angle of feed of any one of said strips independently of the others.
2. In a tube machine, a mandrel, means 125 for feeding a plurality of strips of paper thereto, and means for simultaneously changing the angle of feed of all of said strips, said means having a plurality of intermediate longitudinally adjustable 130

means for changing the angle of feed of one of said strips independently of the others.

3. In a tube machine, a mandrel, means for feeding a plurality of strips of paper thereto from opposite sides, means for simultaneously changing the angle of feed of the strips on one side of the mandrel, and means for simultaneously changing the angle of feed of all of the strips on the other side of the mandrel.

4. In a tube machine, a mandrel, means for feeding a plurality of strips of paper thereto from opposite sides, means for simultaneously changing the angle of feed of all of the strips on one side of the mandrel, means for simultaneously changing the angle of feed of all of the strips on the other side of the mandrel, and means for changing the angle of feed of any of said strips independently of the others.

5. In a tube machine, a mandrel, means for feeding a strip of paper thereto, a slidably and pivotally mounted guide roll for the paper adjacent the mandrel, and means for simultaneously sliding and turning said guide roll to change the angle of feed of the paper to the mandrel.

6. In a tube machine, a mandrel, means for feeding a strip of paper thereto, a guide roll for said strip of paper angularly disposed with relation to the mandrel, and means for sliding said guide roll to change the angular relationship between said guide roll and the mandrel.

7. In a tube machine, a main frame having guide ways formed thereon, a mandrel carried by said frame above the guide ways, means for feeding strips of paper to said mandrel, supports mounted on said guide ways, a guide roll carried by each of said supports adjacent the mandrel, and means for sliding said supports on the guide ways.

8. In a tube machine, a main frame having guide ways formed thereon, a mandrel carried by said frame above the guide ways, means for feeding strips of paper to said mandrel, supports mounted on said guide ways, a guide roll pivotally mounted on each of said supports adjacent the mandrel, and means for sliding said supports on the guide ways.

9. In a tube machine, a main frame having guide ways formed thereon, a mandrel carried by said frame above the guide ways, means for feeding strips of paper to said mandrel, supports slidably mounted on said guide ways, a guide roll carried by each of said supports adjacent the mandrel, and means for sliding said supports.

10. In a tube machine, a main frame having guide ways formed thereon, a mandrel carried by said frame above the guide ways, means for feeding the strips of paper to the mandrel, supports slidably mounted on said guide ways, a guide roll pivotally

mounted on each of said supports adjacent the mandrel, and means for sliding said supports.

11. In a tube machine, a main frame, a mandrel carried by said frame, means for feeding a strip of paper to said mandrel, a support slidably mounted on the frame, a guide roll for the paper having a pivotal mounting on said support, and means for sliding said support longitudinally of the frame to swing the guide roll on its pivot.

12. In a tube machine, a mandrel, an applicator, independently supported at one side of the mandrel, means for feeding paper through said applicator to the mandrel, a guide roll for the paper angularly disposed adjacent the mandrel, and means for changing the angular relationship between said applicator and guide roll and the mandrel.

13. In a tube machine, a mandrel, an adjustable applicator independently supported at one side of the mandrel, means for feeding paper through said applicator to the mandrel, a guide roll for the paper angularly disposed adjacent the mandrel, and means for simultaneously changing the angular relationship between said guide roll and mandrel and adjusting said applicator.

14. In a tube machine having a mandrel, an applicator for applying a coating composition to a strip of paper passing therethrough to the mandrel, comprising a lower member, a guide roll carried by said member, an upper member, a guide roll carried by said upper member, and means adjacent the line of travel of paper over said rolls for pivotally connecting said lower and upper members to permit variation in the angle of feed of the paper to the mandrel.

15. A paper guiding device for tube machines, comprising an applicator having a movable portion through which the paper passes, a guide roll, frame members connecting the movable portion of the applicator with the guide roll, means permitting relative movement between said frame members and said guide roll, and means for adjusting the movable portion of the applicator, the frame members and guide roll to change the angle of feed of the paper.

16. A paper guiding device for tube machines having removable mandrels adapted to produce tubes of different diameters, comprising an applicator having a relatively movable portion through which the paper passes, a guide roll, frame members rigidly secured to the movable portion of said applicator and having a pin and slot connection with said guide roll, and means for adjusting the movable portion of the applicator, the frame members and guide roll to change the angle of feed of the paper in accordance with the diameter of the tube to be produced.

17. In a tube machine, a mandrel, means for feeding paper thereto, belts for winding the paper on the mandrel and pressing the same into position, means for changing the angle of feed of the paper, and means for adjusting the position of said winding belts.

18. In a tube machine, a mandrel, means for guiding paper thereto, said means comprising an applicator, a guide roll, means loosely connecting said applicator and guide roll, and rods for adjusting the position of the applicator and guide roll.

19. In a tube machine, a mandrel, means for guiding a plurality of strips of paper thereto, said means comprising a plurality of applicators, a plurality of guide rolls, means

for connecting each of said applicators to a guide roll, a rod for moving all of said guide rolls, means for moving said rod to 20 simultaneously adjust all of the applicators and guide rolls, and means for individually adjusting any one of said applicators and guide rolls independently of the others.

20. A paper guiding device for feeding 25 paper to the mandrels of tube machines, comprising an applicator frame having a movable portion, a slidably and pivotally mounted guide roll, and frame members connecting said movable portion and said guide roll for simultaneously sliding and swinging said guide roll as the movable portion of the applicator is moved.

FRANK B. YINGLING.
